ELECTRIC POWER APPARATUS

William Toward, Poland Mines, and Alexander Toward, Eightyfour, Pa.

Application October 16, 1935, Serial No. 45,366

1 Claim. (Cl. 172—126)

This invention relates to an electric power apparatus providing reciprocating movement adapted for use in connection with the operation of power rams and hammers, mine shaft gates and mine car movements, or for any other purposes wherein it is found to be applicable.

Important objects of the invention are to provide a power apparatus of the character described, which may be employed as a power device for operating various mechanisms, which may be controlled from points remote therefrom, which is simple in its construction and arrangement, which embodies few moving parts, which is quick and positive in its action, and economical in its manufacture, operation and maintenance.

With the foregoing and other objects in view, which will appear as the description proceeds, the invention resides in the novel construction, combination, and arrangement of parts herein specifically described and illustrated in the accompanying drawings, but it is to be understood that the latter is merely illustrative of an embodiment of the invention, and that the actual needs of practice and manufacture may require certain mechanical variations from the embodiment shown. It is, therefore, not intended to limit the invention to the disclosure thereof herein illustrated, but rather to define such limitations to the scope of the claim hereunto appended.

In the drawings wherein like numerals of reference designate corresponding parts throughout the several views:

Figure 1 is a side elevational view, partly in cross section, of an electric power apparatus constructed in accordance with the invention.

Figure 2 is a diagrammatic view of the wiring and switch element involved in the operation of the device.

Figure 3 is a top plan view of the adjustable connecting elements embodied in the present invention.

Figure 4 is a side elevational view, partly in cross section, of a modified embodiment of the invention.

Figure 5 is an enlarged bottom plan view of the core or armature and stabilizer mounted in the associated cylinder, the latter being in cross section.

Figure 6 is an enlarged, fragmentary, cross sectional view of the stabilizer.

Referring in detail to the drawings, Figure 1 illustrates a horizontally disposed, electrically operated, power apparatus, comprising an elongated tubular cylinder 1 constructed from any suitable, non-magnetic material. A plurality of solenoids

2 are mounted on and surround the cylinder 1. An important feature of the present invention is that the solenoids 2 are positioned flatly against each other on the cylinder 1, and each is distinct and separable from the others, whereby any of the solenoids may be readily removed from or replaced on the cylinder 1, when required for repairs or any other purposes.

A cylindrical core or piston armature 3, of any suitable construction, is shiftably mounted for longitudinal movement in the horizontally disposed cylinder 1. A forwardly projecting piston rod 4 and a rearwardly projecting stabilizing rod 5 have their inner ends fixed, in any suitable manner, in the diametric centers of respective ends of the piston armature 3, and are longitudinally aligned relatively to each other, and with respect to the piston armature 3.

The cylinder 1, with its associated elements, is carried by a pair of suitable bearing supports 6, which engage respective ends thereof, and are fixed on a suitable base 7. Each of the bearing supports 6 is provided with a pair of vertically aligned, revolvably mounted, grooved guide wheels 8, which engage the piston rod 4 and the stabilizing rod 5, respectively, for the purpose of maintaining the accurate alignment of the armature 3 and rods 4 and 5 in the cylinder 1, and to permit the reciprocal movements of these elements in the latter with a minimum of friction, during the operation of the device in the manner to be described.

The upper or top portions 9, of the bearing supports 6, are detachable to permit their removal and thereby allow the ready removal of the cylinder 1 and associated parts from the bearing supports 6 when required for any purpose.

The piston armature 3 and the rods 4 and 5 are held against rotation in the cylinder 1, by means of an arm 10, which is on the inner end 40 portion of the piston rod 4 and has its free end engaged in a longitudinally extending groove 11 formed in the inner wall of the cylinder 1.

The outer end of the piston rod 4 is formed with a socket head 12 carrying a set screw 13, whereby suitable work engaging elements may be attached to or engaged by the outer end of the piston rod 4. In the embodiment illustrated in Figures 1 and 3, a grooved adjusting bar 14 is provided, including a shank 15, which extends 50 into the socket head 12 and is secured in the latter by means of the set screw 13. The work engaging elements further include a clevis 16, suitably apertured for the reception of a connecting pin 17. The clevis 16 is provided with 55

a fixed connecting bar 18 adjustably engaged in the grooved adjusting bar 14. The latter carries a set screw 19 for securing the connecting bar 18 in the adjusted position. By this arrangement, the adjusting bar 14 may be adjusted to any angle on the socket head 12, and the clevis 16 may be adjusted to any required position on the adjusting bar 14.

Our improved power apparatus is particularly 10 adapted for shifting mine cars, and Figure 1 illustrates the attachment of the connecting elements with a mine car 20. If the shifting of the cars can be effected by a pushing operation and no holding or other control is required, the use 15 of the connecting pin 17 is not necessary, but the use of the latter is essential for pulling operations, and when the holding or other control operations are required.

It will here be noted that while the rod 5 is 20 primarily intended for stabilizing the reciprocal movements of the armature 3 and piston rod 4 during the operation of the device, the said stabilizing bar 5 may also be provided with connecting elements or employed as a power imparting member for effecting any operations wherein it is found to be applicable.

The wiring arrangement, illustrated in Figure 2, provides for the manual control of the power apparatus. The negative terminals 21 of the 30 solenoids 2 all join with one main conductor 22 of the electrical source of supply, while the other main conductor 23 is connected with a switch contact bar 24, which is pivoted, centrally of its length, on a switch plate 25. The 35 positive terminals 26 of the solenoids 3 are connected with respective contacts 27 mounted in the switch plate 25. The contacts 27 are arranged for alternate contacting engagement by respective ends of the switch bar 24, so that the 40 solenoids 3 will be energized consecutively in the sequence of their positions on the cylinder 1, and so that an energized solenoid will not be de-energized until the following solenoid is energized to thereby exert the greatest attraction to 45 effect the shifting of the armature 3 in the cylinder 1.

By shifting the contact bar 24 alternately in the clockwise and counter-clockwise directions to engage respective contacts 27, the solenoids 2 50 will be energized in their proper sequence to effect the horizontal reciprocal movement of the piston armature 3 and of the rods 4 and 5 fixed to the latter. The length of the stroke is, of course, determined by the length of the cylinder 55 1 and the associated solenoids 2. The movement of the armature 3 is arrested or stopped and held in the cylinder 1 by stopping the movement of the contact bar 24 while the latter is engaged with any of the contacts 27 to thereby energize 60 respective solenoids, whereby the armature 3 may be held against movement at any required point in the cylinder 1. When the contact bar 24 is in the neutral position, as shown, all solenoids are deenergized and the armature is free and idle in 65 the cylinder 1.

In the modified form of the device, shown in Figure 4, the power apparatus is disposed vertically, and comprises a vertically extending cylinder 21 fixed on a suitable base 22. Solenoids 23 70 surround the cylinder 21 and are positioned in super-imposed relation to each other.

A cylindrical piston armature 24 is shiftably mounted for vertical movement in the cylinder 21. A piston rod 25 is fixed in the armature 24 75 and extends vertically upward through a suitable

bearing 26 mounted on the top of the cylinder 21. The bearing 26 includes a pair of grooved guide wheels 27, which engage the piston rod 25.

The modified form of the apparatus is illustrated as applied for operating a vertically shiftable mine shaft gate 28. The latter is arranged for being opened and closed, and is shiftably engaged on a pair of spaced, vertically extending guide bars 29. Stop members 30 are carried by the guide bars 29 to limit the elevating movement of the gate 28. A pair of coil springs 31 is shiftably mounted on the guide bars 29 above the gate 28 for cushioning the impact of the latter when reaching its elevated or open position. A pair of coil springs 32 are mounted on the guide 15 bars 29 below the gate 28 for cushioning the impact of the latter when reaching its lowered or closed position.

The outer end of the piston rod 25 is provided with an eye member 33, and a cable 34 has one 20 end thereof secured in the latter. The cable 34 passes over suitably positioned sheaves 35 and has its other end secured to the gate 28.

The gate 28 is intended to shift to the lowered or closed position by gravity, and counter-weights 25 36 are mounted on the upper end portion of the piston rod 25 to permit the positive closing or lowering of the gate 28 by gravity, but requiring a relatively small amount of power to shift said gate 28 to the open or elevated position.

A stabilizing member 37 is fixed, by means of a bolt 38, in the diametric center of the lower end of the armature 24 for stabilizing the latter and maintaining same in proper alignment in the cylinder 21. The stabilizing member 37 35 comprises a hub 39 provided with a plurality of radially disposed, hollow arms 40. A wall engaging element 41 is carried by each of the arms 40 and radially shiftable in the latter.

Each of the elements 41 comprises a revoluble 40 member 42, preferably in the form of a ball, which is mounted in a suitable casing 43. The latter is provided with a fixed stem 44 extending into outer open end of respective arms 40. A coil spring 45 is mounted in each of the arms 40 and engages the inner end of the stem 44 for tensionally forcing the revoluble member 42 against the inner wall of the cylinder 21, to effect the stabilization of the armature 24 in the latter. One or more vertically extending grooves 46 may 50 be formed on the inner wall of the cylinder 21 to provide definite paths of travel for the revoluble members 42 for preventing the turning of the armature 24 and associated piston rod 25 in the cylinder 21.

A vertically disposed contact bar 47 is fixed to the base 22 and bearing 26. A contact 48, for each of the solenoids 23, is fixed in the bar 47 and joins with the positive terminal 49 of respective solenoids 23. The contacts 48 are vertically 60 aligned and equally spaced from each other.

A substantially L-shaped, resilient contact support 50 is fixed to the upper end portion of the piston rod 25, and its connection with the latter provides a seat for the counter-weights 36. An 65 elongated contact member 51 is fixed against the inner side of the lower end portion of the support 50, and is of a length to simultaneously contact with one or two adjacent contacts 48 on the latter, as illustrated in Figure 4.

One of the main conductors 52 of the electrical source of supply is connected with the contact member 51, and the other connects with the terminals 53 of the solenoids 23.

When the solenoids 23 are deenergized, the gate 75

28 will shift by gravity to the lowered or closed position, and the piston armature 24 will be in the elevated position in the cylinder 21, as shown in Figure 4. To elevate the gate 28, the control 5 switch is closed to energize the uppermost of the solenoids 23, whereby the armature 24 will be attracted to shift downwardly in the cylinder 21. As the piston rod 25 carries the fixed contact support 50, the downward travel of the latter will 10 cause the contact member 51 to engage the contacts 48 on the contact bar 47 and thereby energize the solenoids 23 in the sequence of their positions on the cylinder 21, whereby the gate elevating operation is effected automatically, except for 15 closing the control switch at the start of the elevating operation. The gate 28 will be held in its elevated position as long as the lowermost solenoids 23 remain energized, and when the latter are deenergized, by opening the control 20 switch, the gate 28 will shift to the lowered or closed position, and draw the armature 24 to the top of the cylinder 21 for subsequent elevating operations.

The present invention provides a most efficient power apparatus of the character set forth, 25 which may be operated and regulated by remote

control, which may embody control elements capable of providing automatic and continuous reciprocal motion, and which may be successfully employed in many various types of mechanisms operable by connection therewith. 5

What we claim is:

In an electro-magnetic power mechanism of the character described, the combination of a tubular cylinder, a plurality of solenoids mounted on and surrounding said cylinder, a reciprocating 10 core mounted in said cylinder, means for supporting said core in said cylinder, the inner face of said cylinder being provided with a plurality of longitudinally extending grooves, a hub fixed to said core, a plurality of radially disposed hollow 15 arms secured to said hub, a stem mounted in and radially shiftable in each of said arms, a casing fixed to the outer end of each of said stems, a revolute ball carried in each of said casings, and a spring mounted in each of said hollow arms and 20 engaging respective stems for tensionally forcing said revolute balls into said grooves for stabilizing said core in said cylinder.
